F. W. Brocksieher
Inventor

United States Patent Office.

F. W. BROCKSIEPER, OF NEW HAVEN, CONNECTICUT, ASSIGNOR TO SARGENT AND COMPANY, OF SAME PLACE.

Design No. 3,021, dated May 12, 1868.

DESIGN FOR A BRACKET.

The Schedule referred to in these Letters Patent and making part of the same.

TO ALL WHOM IT MAY CONCERN:

Be it known that I, F. W. BROCKSIEPER, of New Haven, in the county of New Haven, and State of Connecticut, have invented a new Design for a Bracket; and I do hereby declare the following, when taken in connection with the accompanying drawing, to be a full, clear, and exact description of the same, and which said drawing constitutes a part of this specification, and represents a perspective view.

This invention relates to a design for a wall-bracket formed from cast metal, in imitation of carved wood.

The shelf represents a fully-opened lily, springing from a sprig of thistle, which forms the base of the bracket, resting against the wall, all as clearly seen in the accompanying illustration.

Having thus fully described my invention, what I claim as new, and desire to secure by Letters Patent, is—
The design for a bracket, as herein described and illustrated.

Witnesses:

J. H. SHUMWAY,
A. J. TIBBITS.

F. W. BROCKSIEPER.
